UNITED STATES PATENT OFFICE.

WILLIAM H. SAUVAGE, OF NEW YORK, N. Y., ASSIGNOR, BY MESNE ASSIGNMENTS,
TO ROYAL RAILWAY IMPROVEMENTS CORPORATION, OF NEW YORK, N. Y., A
CORPORATION OF DELAWARE.

REGULATOR FOR BRAKE RIGGING.

Application filed November 12, 1927. Serial No. 232,885.

This invention relates to regulators for the foundation brake gear of railway vehicles and will be hereinafter described with relation to its application at one end instead of the center of a railway car, whereby a lever of the brake rigging having a normally fixed fulcrum point may be adjusted and positioned to insure uniform piston travel and proper brake shoe clearance. The invention hereinafter described embodies an improvement over the type of regulator shown in my co-pending application. Serial No. 157,168, filed December 27, 1926.

Accordingly, one of the main objects of my invention is to provide a mechanism of the above general character which is easily accessible and operative to permit a rapid and accurate adjustment of the brakes and positively hold the parts in such adjusted position until it is again necessary to bring the brake mechanism to a further adjusted position.

Another object of the invention is to provide a mechanism of the above character by which the parts may be readily released after successive adjustments, and returned to initial position, as when it is desired to install new brake shoes.

A further object is to provide a reliable, flexible and efficient mechanism of the above character, having few parts, of simple and practical construction, and which may be easily and quickly applied to brake rigging now in general use without material alteration or modification of parts.

A further object is to provide a reliable mechanism of the above general character which will be fool-proof in operation and in which the working parts will be fully protected from atmospheric conditions and other disturbances.

Other objects will be in part obvious from the annexed drawings and in part herein-after indicated in connection therewith by the following analysis of this invention.

This invention accordingly consists in the features of construction, combination of parts and in the unique relation of the members and in the relative proportioning and disposition thereof, all as more completely outlined herein.

To enable others skilled in the art to fully comprehend the underlying features thereof that they may embody the same by the

numerous modifications in structure and relation contemplated by this invention, drawings depicting a preferred form of the invention have been annexed as part of this disclosure, and in such drawings, like characters of reference denote corresponding parts throughout all of the views, in which—

Fig. 1 is a semi-diagrammatic elevational view of such parts of the general brake rigging construction and associated regulator as will be necessary to understand one embodiment of the invention;

Fig. 2 is a vertical longitudinal section thru the regulator;

Fig. 3 is a transverse section along lines 3—3 of Fig. 2; and

Fig. 4 is a transverse section showing adjusting means.

Referring now to the drawings and more particularly to Fig. 1, 5 designates the conventional truck bolster, near which one end of a dead lever 6 of the brake rigging normally takes up a position of rest. It will be understood that the lever 6 has a connection at its lower end with a bottom rod 7 extending to a live lever 8 which is actuated from the cylinder levers (not shown) by a pull rod 10. At the top end of the lever 6 there is provided a clevis 11 connected with one or more links 12, which in turn are joined to a shackle 13, thus providing a flexible connection between dead lever 6 and an adjusting rod 14. By reference to Fig. 2, the adjusting rod 14 extends thru a housing or casing 15 which is bolted or otherwise secured to the under side of a car body or draft sill 16 near one end of the car. An opening may be provided in the under side of the casing for assembly or the insertion and removal of the parts to be herein-after described and to prevent the accumulation of dirt therein.

Within the casing is arranged a pawl cage 17 which rides on ratchet teeth 18 disposed on the adjusting rod 14 and is adapted to float freely thereon. A pawl 20 is suitably trunnioned as at 21 within the cage and normally drops into engagement with one of the ratchet teeth 18. A detachable operating handle 22 extends from the rod 14 beyond the casing, and it will be apparent that as the handle and adjusting rod are pulled outwardly, the cage 17 and pawl therein move along the casing 20, to the extent of lost mo-

tion provided for by the difference in length of the cage and housing. This distance is proportional to total truck brake shoe clearance.

According to the present invention, I propose to have the movement permitted the cage and pawl proportional to total brake shoe clearance, whereby movement of the pawl throughout its predetermined stroke or travel brings the brake shoes into engagement with the car wheel peripheries, assuming that no excess travel exists in any part of the brake rigging. Further movement of the handle 22 and rod 14 towards the left, resulting from excess travel of the brakes, causes the adjusting rod or regulating rod 14 to move relatively to pawl 20 the distance of excess travel, and the pawl, by its engagement with the ratchet 18, takes up an adjusted position relative thereto to absorb the excess travel existing in any part of the rigging and permanently holds the same. Upon release of the handle 22, the rod 14 and pawl move back to the position shown in Fig. 1, by gravity action on the lever 6, and the parts are positively held in adjusted position for brake application.

To provide for variation of proper brake shoe clearance as required under different operating conditions or different types of rigging, one or more washers or shims 24 surround the rod 14 between one of the end walls of casing 15 and cage 17. Thus, by adding one or more shims or washers, the travel of the cage 17 and pawl may be varied to meet the varying requirements of brake shoe clearance.

The ratchet rod 14 is circular, or substantially so, in cross section, and supports the shims as shown in Fig. 4. To effect release of the regulator, it is necessary to turn the rod 14 a quarter turn more or less as permitted by the flexible link connection 12 to effect disengagement of the pawl 20 from the ratchet 18, and the rod 14 is permitted to move relatively thereto to return the brake gear to its full release position and permit the insertion of new brake shoes, for example.

Altho the regulator has been described in the foregoing as being fixed to the draft sill and operative to regulate the adjusting rod connected to the dead lever, it is equally applicable as a normally fixed support for any of the levers of the foundation brake rigging and by its regulating features serves to so position the lever with which it is associated as to insure predetermined brake shoe clearance and predetermined piston travel upon application of the brakes.

It will be understood that the regulator as above described should be used with the general type of brake gear shown in my prior Patent, No. 1,612,781, dated December 28, 1926, in so far as the hanger or stop limiting

means for the cylinder levers are concerned.

From the above, it will be seen that the present invention provides a reliable, flexible, fool-proof and efficient mechanism of simple and practical construction and well adapted to accomplish, among others, all of the advantages and objects herein set forth. 70

Without further analysis the foregoing will so fully reveal the gist of this invention that others can by applying current knowledge readily adapt it for various applications without omitting certain features that, from the standpoint of the prior art, fairly constitute essential characteristics of the generic or specific aspects of this invention, and therefore such adaptations should and are intended to be comprehended within the meaning and range of equivalency of the following claims. 80

I claim— 85

1. In combination with a lever of the foundation brake gear, a variable regulator therefor including an adjusting rod having ratchet teeth thereon, a freely floating cage resting on said rod, and a pawl mounted in said cage and abutting an end wall thereof for engagement with said ratchet teeth, said adjusting rod having a substantially circular cross section whereby, upon turning of said rod, the pawl is disengaged 90 from said ratchet. 95

2. In combination with a lever of the foundation brake gear, a regulator therefor including a casing, an adjusting rod extending thru said casing and having ratchet teeth thereon, a floating cage mounted in said casing and resting on said adjusting rod, a pawl mounted in said cage for engagement with said ratchet teeth, and freely movable means operative between said casing and said cage to vary the movement of said cage relative to said casing. 100 105

3. In combination with a lever of the foundation brake gear, a regulator therefor including a casing, an adjusting rod extending thru said casing and having ratchet teeth thereon, a floating cage mounted in said housing and resting on said adjusting rod, a pawl mounted in said cage for engagement with said ratchet teeth, and shims 110 resting on said ratchet rod and arranged to vary the travel of said cage relative to said casing. 115

4. In a regulator for foundation brake gear, an adjusting rod having a connection with one of the levers of said brake gear, a housing thru which said rod extends, said rod having ratchet teeth thereon, a floating pawl mounted in said casing and normally engaging said ratchet teeth, said pawl being permitted movement relative to said casing proportional to brake shoe clearance, and shims operative between said casing and pawl to vary the travel of said pawl. 120 125

5. In a regulator for foundation brake 130

- gear, an adjusting rod having a connection with one of the levers of said brake gear, a casing thru which said rod extends, said rod having ratchet teeth thereon, a cage in said housing resting on said ratchet teeth, a pawl mounted in said cage and normally in engagement with one of said ratchet teeth, said cage and pawl being permitted movement in said housing proportional to 10 brake shoe clearance, and one or more shims in said casing and operative between said casing and said cage to vary the amount of travel of said cage and pawl.
6. In a regulator for foundation brake gear, a regulating rod of substantially circular cross section having a connection with one of the levers of said brake gear, a hous- ing thru which said adjusting rod extends, said rod having ratchet teeth thereon, a cage in said housing adapted to float on said ratchet teeth, a pawl trunnioned in said cage, and normally in engagement with one of said ratchet teeth, said cage and pawl permitted movement in said housing proportional to 20 brake shoe clearance, and an adjustable means operative between said casing and said cage to vary the travel of said cage and pawl, the said pawl and rod being disengageable upon turning of said adjusting rod thereby to return the parts 25 to full release position.
15. Signed at New York, New York, this 3rd day of November, 1927.

WILLIAM H. SAUVAGE.
